UNITED STATES PATENT OFFICE.

HARRISON B. BOZARD, OF HAMILTON, ONTARIO, CANADA, ASSIGNOR, BY MESNE ASSIGNMENTS, TO INTERNATIONAL HARVESTER COMPANY, OF CHICAGO, ILLINOIS, A CORPORATION OF NEW JERSEY.

DOUBLE-DISK SCRAPER.

1,410,883.

Specification of Letters Patent. Patented Mar. 28, 1922.

Application filed October 10, 1918. Serial No. 257,560.

To all whom it may concern:

Be it known that I, HARRISON B. BOZARD, a citizen of the United States, residing at Hamilton, in the county of Wentworth and

5 Province of Ontario, Dominion of Canada, have invented certain new and useful Improvements in Double-Disk Scrapers, of which the following is a full, clear, and exact specification.

10 This invention relates to scrapers for double disk drills.

The object of the invention is to scrape the mud and dirt from the inner surfaces of double disk drills so that these foreign substances will not interfere with the proper working of the implement.

15 A further object is to provide an improved scraper that will have at all times a proper bearing contact with the inner surfaces of the disks and will perform the scraping function with less wear than has heretofore been possible.

20 A further object is to provide a combination of adjustable scrapers formed in such a manner that the entire inner surfaces of the disks will be thoroughly scraped and cleared of all mud and dirt.

25 These objects are attained in the present instance by providing a plurality of adjustable scrapers, the scrapers being so formed that they will have the proper bearing contact with the inner disk surfaces, and also in such a manner that they may be adjusted to take up the slight wear that occurs, the 30 wear in the scrapers employed being much less than that ordinarily experienced.

35 In the accompanying drawings I have illustrated one embodiment of my invention, and in these drawings,—

40 Figure 1 shows in perspective a grain drill boot with my improved scrapers secured thereto, one of the disks of the double disk drill being omitted from the showing in order to clearly show the construction of the 45 scrapers;

Fig. 2 is a side elevation of the rear portion of the boot illustrating the mounting of one of the scrapers; and

50 Fig. 3 is a bottom plan view of the double disk drill having the improved scrapers thereon.

In the construction illustrated the boot 10 is of the usual construction and has a for-

wardly projecting portion 11 which is secured by drag bars to the transporting frame, a rearwardly projecting portion 12 and an inwardly projecting bearing stem 13. The disks 14, one of which is illustrated, may be secured to the bearing stem in any suitable manner. The stem 13 has formed 60 on its rear side a flanged portion 15 and this flange is cut away as shown at 16 adjacent the rearwardly extending portion 12 of the boot in order to provide clearance and allow accumulations of dirt which break away 65 from the outer scraper hereinafter described, to pass without clogging the disks. These accumulations will be removed upon the succeeding revolution of the disk. The flange portion 15 of the bearing stem is provided 70 with adjustable scrapers 17 which are secured to the bearing stem by means of screws 18; these scrapers may be accurately adjusted to proper bearing contact with the inner surfaces of the disks, and when so 75 adjusted they remove all trash and dirt from the inner surfaces of the disks and prevent these substances from coming into contact with the ribbon tube or other parts of the boot located in advance of the bearing stem. 80 The rear portion or tail 12 of the boot is curved downwardly and inwardly as shown at 19, a transverse rib 20 being provided adjacent the curved end of the boot. In order to clear the mud and dirt from the outer 85 portion of the inner surfaces of the disks, a scraper 21 preferably formed with chilled edge portions 22, is adjustably secured by means of a screw 23 to the curved tail portion 19 of the rearwardly extending portion 90 of the boot. The screw 23 passes through the slot 24 in the scraper and is spaced from the scraper by means of a washer 25. In this manner the scraper is longitudinally adjustable on the tail 19 of the boot. The upper 95 portion of the scraper is curved transversely to conform to the curvature of the rib 20, and this portion bears against the rib 20, the bearing contact of the scraper with the tail portion being limited to the upper end which 100 bears against the rib 20 and a portion which is immediately adjacent the securing screw 23. This leaves the lower portion of the scraper free to move with respect to the lower end of the tail 19 of the boot thereby providing a resilient construction. The extreme 105

upper edge of the scraper is notched as shown at 26 to position the drag chain in its proper central position so that the chain will not work over the side of the scraper.

5 In working out the longitudinal curvature of the scraper I have found the most satisfactory construction to be that illustrated in the drawings wherein the portion of the scraper between the points 27 and 28 10 is curved and the remaining portion between the points 27 and 29 is substantially straight, and flat, or disposed in a single plane.

In order to provide a proper and efficient 15 bearing contact between this scraper and the outer portion of the inner surfaces of the disks, I have found it advisable to provide a longitudinal recess or slot 30 at the extreme lower end of the scraper, this recess 20 forming a forked or bifurcated end portion on the scraper, the bifurcations 31 and 32 being laterally resilient in order to enable the scraper to conform closely to the inner surfaces of the disks.

25 From the above description it is believed that the operation of the improved construction will be clear, but the following brief description will be given.

The disks rotate in the direction of the 30 arrow shown in Fig. 1, and after the scrapers 17 and the scraper 21 have been adjusted to proper bearing contact with the inner surfaces of the disks, upon rotation the scrapers 17 will remove the dirt and 35 mud from the inner portions of the inner surfaces and the scraper 21 will remove the foreign substances from the outer portion of the inner surfaces. Any material that is forced outwardly toward the periphery of 40 the disk by the scrapers 17 after the action of the scraper 21, will pass through the clearance space 16 formed on the bearing stem and will be engaged by the scraper 21 upon the next succeeding revolution. By 45 providing a scraper 21 having its lower end free to vibrate toward and from the tail portion 19 of the boot, and also by providing this scraper with a bifurcated lower end and a substantially flat end portion, a construction has been provided which will conform 50 very closely to the inner surfaces of the disks and will be maintained in proper bearing contact therewith.

By chilling the outer edges 22 of the 55 scraper 21, I have greatly increased the life of the scraper and decreased the wear.

From the above description it will be seen that a simple and efficient construction has been provided, and a construction that will 60 satisfy all the requirements and will perform the functions with a minimum amount of wear.

While I have in the above specification described one embodiment of my invention, 65 it will be understood that the invention is

capable of modification, and that modifications may be made without departing from the spirit and scope of the invention as expressed by the following claims.

What I claim as new is:

1. In combination, a grain drill boot having a curved tail portion, and a scraper secured to said tail portion and extending beyond the same, the portion of the scraper beyond the securing means being free to vibrate toward and from the end portion of the tail of the boot. 70

2. In combination, a grain drill boot having a rearwardly extending portion, a transverse rib being formed on said rearwardly extending portion near the free end thereof, and a scraper secured to said rearwardly extending portion and having its upper free end bearing against said transverse rib. 75

3. A scraper for double disk grain drills having a notch at one end for the reception of a drag chain. 85

4. A scraper for double disk grain drills having its upper portion longitudinally and transversely curved and its lower end bifurcated and formed of resilient material. 90

5. A scraper for double disk grain drills having its upper portion longitudinally and transversely curved and its lower portion substantially flat. 95

6. A scraper for double disk grain drills having a notch at one end for the reception of a drag chain and having its other end bifurcated, said scraper being formed of resilient material. 100

7. A scraper for double disk grain drills having a portion curved longitudinally and the remaining portion substantially flat, the flat portion being bifurcated.

8. A scraper for double disk grain drills having a portion curved longitudinally and the remaining portion substantially flat and having a notch formed at one end for the reception of a drag chain and a longitudinal recess at its opposite end. 105

9. In combination, a grain drill boot having a rearwardly extending portion and an inwardly extending bearing stem, said bearing stem being recessed toward its one end and having adjustable scrapers secured on 115 its other end, and said rearwardly extending portion having secured thereto at its rear end a resilient scraper provided with a bifurcated free end.

10. In combination, a grain drill boot having a rearwardly extending portion and a scraper secured to said rearwardly extending portion having integral laterally resilient portions at its free end. 120

11. In combination, a grain drill boot having a rearwardly extending portion and a scraper adjustably secured to said rearwardly extending portion with a portion of said scraper spaced from the extreme rear end of said rearwardly extending portion of 125 130

the boot and said scraper having its free end extending beyond the rearwardly extending portion of said boot.

12. In combination, a grain drill boot having an inwardly extending bearing stem, and scrapers secured to said bearing stem and adjustable laterally thereon.

13. In combination, a grain drill boot having a rearwardly extending portion and an inwardly extending bearing stem, laterally adjustable scrapers secured to said bearing stem, and a scraper secured to said rearwardly extending portion and having laterally resilient portions at its free end.

15. 14. In combination, a grain drill boot hav-

ing a curved tail portion and a scraper secured to said tail portion and having a longitudinally curved portion, the radius of curvature of the tail portion of said boot being shorter than the radius of curvature 20 of the curved portion of said scraper.

15. In combination, a grain drill boot, a resilient scraper blade having lateral edge portions resiliently yieldable in a plurality of directions at right angles to each other 25 and means for rigidly clamping said scraper blade to said boot.

In testimony whereof I affix my signature.

HARRISON B. BOZARD.
